United States Patent Office

Des. 188,105

Patented June 7, 1960

188,105

ELECTRICAL CONNECTOR

Robert F. Cobaugh, Rte. 88, Harrisburg, Pa.

Filed Apr. 24, 1957, Ser. No. 45,878

Term of patent 14 years

(Cl. D26—1)

FIG. 4

Figure 1 is a perspective view of an electrical connector, showing my new design;

Figure 2 is a perspective view showing the opposite side;

Figure 3 is an end elevational view; and

Figure 4 is an opposite end elevational view thereof.

The dominant features of my new design are shown in solid lines in the drawing.

I claim:

The ornamental design for an electrical connector, substantially as shown and described.
